UNITED STATES PATENT OFFICE.

JOHN H. ROOK, OF JONESBOROUGH, INDIANA, ASSIGNOR OF ONE-HALF TO
B. F. BURK, OF SAME PLACE.

PUMP.

SPECIFICATION forming part of Letters Patent No. 331,734, dated December 1, 1885.

Application filed September 1, 1885. Serial No. 175,877. (No model.)

To all whom it may concern:

Be it known that I, JOHN H. ROOK, a citizen of the United States, residing at Jonesborough, in the county of Grant and State of Indiana, have invented certain new and useful Improvements in Pumps; and I do hereby declare the following to be a full, clear, and exact description of the invention, such as will enable others skilled in the art to which it appertains to make and use the same.

My invention relates to improvements in pumps, and it is designed to produce a non-corrosive cylinder for the reception of the plunger, and also a means whereby the same may be connected to the pump-stock and to the pipe extending into the well or reservoir.

In the following description reference is had to the annexed drawings, in which Figure 1 represents a vertical section of the device; Fig. 2, a plan view of the reducer; and Fig. 3, a cross-section through the pump-stock, showing the clamp.

A designates a cylinder, preferably of metal, with an internally-screw-threaded shoulder, B, at the lower end, and reduced at the upper end, forming an annular shoulder, C. An exteriorly-tapering continuation, D, is formed on the top of said cylinder, as shown.

Within the cylinder A is secured a glass cylinder, E, having on its upper end an annular exterior flange, F, which rests against and under the shoulder C, thus aiding in keeping the two cylinders in proper relation one to the other. Between the walls of the two

cylinders is interposed the cement G, which firmly secures the glass cylinder in place, lugs or flanges H being provided on the interior surface of the cylinder A to prevent all danger of the cement slipping. Within the glass cylinder operates the plunger I, which may be of any approved construction. The bore in the pump-stock K flares at the bottom, as shown at L, and receives the continuation D. Surrounding the pump-stock is a clamp consisting of two parts or frames, M, secured together at the coincident projecting ends N by bolts or keys O. The shape of the clamp conforms to the shape of the stock or pipe. A similar clamp, P, encircles the pipe R be-

low the cylinder, and each clamp is provided 50 with eyes S, one on each side being sufficient.

On the cylinder A, near both top and bottom, are eyes T. Through the eyes S and T pass the securing-bolts U, one end of each of which may be slotted to receive a wedge, as 55 shown. The shoulder B receives a reducer, V, internally tapering and screw-threaded externally, and provided with an outwardly-projecting annular flange, W, which has recesses X for the reception of a wrench. Within 60 in the reducer fits the tapering end of the pipe R, which is surmounted by a valve, Y. It is clearly evident that as the bolts U are drawn up they will force the tapers on the cylinder, pipe, and stock in close conjunction, making a tight and secure joint and keeping the parts of the pump in line. The use of glass for the cylinder in which the plunger operates absolutely prevents wear on the packing of said plunger, and hence obviates 65 all danger of leakage or ineffective operation. The cement is of sufficient thickness to join the outer and inner cylinders, the outer one being large enough to allow for the taper-joints and the clamps. 70

I claim—

1. Combined with a pump-stock having its lower end provided with an interior taper, a plunger-cylinder having an integral reduced continuation provided with an exterior taper, 8c and having its interior diameter about the same as that of the said cylinder and pump-stock, substantially as specified.

2. Combined with a cylinder having an integral reduced externally-tapered continuation, a glass cylinder interior thereto and provided with an annular flange resting under said reduced portion, a removable ring fitting one end of said exterior cylinder and provided with an internal taper, a pump-stock with the 85 lower end internally tapered, a pipe with an end externally tapered, and clamps holding the parts in conjunction, substantially as specified.

3. A pump having a plunger-cylinder, with 95 an externally-tapering reduced continuation at one end and at the other an internally-tapering removable reducing-ring, combined

with a stock having an internal taper at its lower end, a pipe with an exterior taper at one end, and clamps for securing the cylinder, stock, and pipe, substantially as and for the purpose specified.

4. A pump-plunger cylinder with an interior glass surface, combined with an exterior cylinder having reduced tapering ends and exterior eyes, a pump-stock having an interior taper to fit the cylinder, a pipe with an exterior taper to fit the cylinder, and clamps formed

of frames surrounding the stock and the pipe and secured to the eyes on the cylinder by bolts, substantially as and for the purpose specified.

In testimony whereof I affix my signature in presence of two witnesses.

JOHN H. ROOK.
